UNITED STATES PATENT OFFICE.

CYRIL MARWOOD AND AVERELL KIDD, OF BLACKBURN, ENGLAND.

GOLF BAG.

Application filed June 20, 1921. Serial No. 479,168.

To all whom it may concern:

Be it known that we, CYRIL MARWOOD and AVERELL KIDD, residing at Blackburn, in the county of Lancaster, England, have invented 5 certain new and useful Improvements in Golf Bags, of which the following is a specification.

This invention relates to golf bags and has for its chief object to construct same in such 10 manner that the wooden clubs cannot be injured by frictional contact with the iron clubs. In the ordinary type of bag all the clubs are carried indiscriminately in one compartment and the continued friction of 15 the iron clubs upon the wooden clubs as the latter are withdrawn from and returned to the bag scratches the varnish and wears away the shafts and as the iron clubs are withdrawn from and returned to the bag 20 they are apt to wear away and cut the wrapping which secures the spliced or socketed wooden heads to the shafts.

According to this invention in order to prevent such injury, the bag is so constructed and arranged that the wooden clubs 25 are kept separate from the iron clubs and incapable of coming in contact therewith as they are withdrawn from and returned to the bag, the iron clubs being in like manner 30 prevented from coming in contact with the wooden clubs whilst undergoing a similar operation.

For this purpose a partition may extend across the mouth of the bag to separate same 35 into two openings which may be of different sizes, the smaller opening being for the wooden clubs. If desired such partition may extend throughout or partly throughout the length of the bag. The mouth of the 40 latter is advantageously stepped, that is to say the top of the opening for the wooden clubs lies above the top of the opening for the iron clubs. To prevent the wooden clubs being knocked, or damaged by the iron clubs 45 as the latter are withdrawn from the bag a shield or projection may be arranged between the two openings to deflect the heads of the iron clubs away from the wooden clubs. If desired the top of the bag may be 50 fitted with a flap or cover to cover up the club heads when required.

In the accompanying drawings:—

Fig. 1 is a perspective view and Fig. 2 a side view partly in section of a golf bag constructed in accordance with this invention.

Fig. 3 is a section showing the partition extending throughout the length of the bag.

Fig. 4 is a side view partly in section showing the top of the bag arranged at an incline instead of being stepped and, 60

Fig. 5 shows the device made as an attachment to an existing bag.

A indicates the partition or shield, B the opening for the iron clubs, and C the opening for the wooden clubs. 65

In the examples shown in Figs. 1 to 3 the top of the bag is stepped and the partition A constitutes a shield which operates in the manner previously described. In Fig. 3 the partition A is extended downwardly 70 throughout the length of the bag and in Fig. 4 the top of the bag is arranged at an incline instead of being stepped. Fig. 5 shows the top of a bag adapted to be used as an attachment to an existing bag. 75

The top edge of the bag is folded over and secured to its main portion, and a stiffening member 5 of stout wire is inclosed in the fold 4 thus formed. This stiffening member is bent to conform to the step-shaped form of 80 the mouth of the bag, and it and the fold form a continuous and rigid re-inforcing member which extends completely around the mouth of the bag and holds it wide open. The front portion of the re-inforcing member is arranged at a lower level than its back portion 6 behind the partition A, and the sling 7 for carrying the bag is secured to the middle of the back portion 6 and to the body 85 of the bag beneath it. 90

What we claim is:

In a golf bag, a bag having a step-shaped mouth the top of the front side of which is arranged at a lower level than the top of its rear side, the said mouth being provided 95 with a continuous and rigid re-inforcing member extending completely around it and holding it open, a partition secured to the bag and dividing its upper portion into two compartments, the top of the said partition being arranged above the level of the front edge of the mouth, and a carrying sling secured to the middle of the rear part of the said re-inforcing member and to the body of the bag beneath it. 100

In testimony whereof we affix our signatures.

CYRIL MARWOOD.
AVERELL KIDD.
